UNITED STATES PATENT OFFICE.

WILLIAM T. GILBERT, OF OSWEGO, KANSAS.

WINDOW CATCH AND LOCK.

SPECIFICATION forming part of Letters Patent No. 351,261, dated October 19, 1886.

Application filed May 27, 1886. Serial No. 203,451. (No model.)

To all whom it may concern:

Be it known that I, WILLIAM T. GILBERT, a citizen of the United States, residing at Oswego, in the county of Labette and State of Kansas, have invented certain new and useful Improvements in Window Catches and Locks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to certain new and useful improvements in window catches and locks, the object of the same being to provide a means whereby the upper and lower sashes can be adjusted independent of each other, said sashes 20 being held in position by a rod which is fixed to the window-frame. Said rod passes through a keeper attached to one of the sashes, the other sash being provided with a catch for engaging with said depending rod.

25 My invention also consists in combining, with a rod having a vertical serrated edge and perforations, a spring-catch attached to the upper sash that may engage with said serrations, and in providing the lower sash with a 30 spring-catch which engages with perforations in said rod, and providing said spring-catches with a cord for operating the same, as will be hereinafter fully set forth, and specifically pointed out in the claims.

35 In the accompanying drawings, which illustrate my invention, Figure 1 is a front view of a window-frame, showing my invention applied thereto. Fig. 2 is a vertical sectional view. Fig. 3 is a detail perspective view of a casing 40 which is attached to the upper portion of the window-frame for holding the depending rod in position. Fig. 4 is a detail perspective view of a spring-catch and casing which is attached to the upper window-sash. Fig. 5 is a 45 perspective view of the spring-casing attached to the upper portion of the lower sash, and Fig. 6 is a plan view of the upper edge of the depending rod.

50 A refers to the window or sash frame, the central portion of the bead of which is cut away so that the metallic plate B, the construction of which is fully shown in Fig. 3,

may embrace said bead. This metallic plate is preferably struck up of a single piece of sheet metal, and is provided with a central 55 depending portion, c, which is provided with a slot, b', and horizontally-extending flanges c c, whereby said plate may be secured to the window-frame. The slot b' is covered, after the rod C has been placed in position, by a bent 60 plate, c', as fully shown in the accompanying drawings. The upper portion of the bar C is provided with notches d d, which engage with the sides of the casing B, adjacent to the slot b', so that said bar or rod will depend therefrom 65 in a vertical position parallel and adjacent to the central portion of the upper sash, D.

The depending bar C, hereinbefore referred to, preferably consists of a flat bar of metal, and it is provided on one side with a series of 70 angular serrations, c c, with which the catch attached to the upper part of the sash D engage. This bar is also provided centrally with perforations c', with which the catch attached to the lower sash-frame, D', will engage. The 75 catch F, as shown in Fig. 4 of the accompanying drawings, consists of a metallic housing, which is struck up of a single piece of sheet metal, so as to provide a guideway, f, through which the rod C will pass, and adjacent to this 80 guideway a recess, g, is formed, within which the spring-catch g' will lie, said catch being forced against the edge of the bar C by means of a spiral spring, g'', which bears against a shoulder formed theron and the end of the 85 housing. The stem of the spring-catch g' passes through a perforation, f', as shown. The housing E is secured to the top bar of the upper sash by means of screws which pass through perforations in the flanges thereof, and the 90 spring-catch is provided with a knob for throwing the same in and out of engagement with the serrated portion of the depending bar C.

The upper rail of the lower sash has attached thereto an ordinary spring-catch, F, which is 95 adapted to engage with the perforations e' of the bar C. The lower rail of the upper sash is recessed, so that the end of the bar C may lie within said recess when the upper sash is raised.

100 For the purpose of conveniently operating the spring-bolts, the upper sash, near one of its corners, is provided with an eye, h, through which passes the cord, one end of said cord

being attached to the knob of the upper spring-bolt, while the opposite end is attached to the knob of the lower spring-bolt. Thus by grasping and pulling upon said cord in an upper direction, these bolts may be released, so as to be thrown out of engagement with the serrations or perforations in the depending bar C.

By means of the device hereinbefore described sash-weights are entirely dispensed with, and said sashes can be adjusted independently of each other and held in position by a bar affixed to the window-frame.

I claim—

1. The combination of a window-frame having a depending bar, C, with a serrated edge and a perforated central portion attached thereto, a spring-catch embracing said bar and attached to the upper edge of the upper sash, so as to engage with a serrated portion, and a spring-catch attached to the upper rail of the lower sash to engage with the perforated portion of said bar, whereby the sash-frame can be adjusted independent of each other, substantially as shown, and for the purpose set forth.

2. In combination with a window-frame, a

depending bar having a slotted upper end, whereby it is attached to a plate secured to the window-frame, said bar having a serrated edge and central perforated portion, a plate, 30 E, attached to the upper sash-frame, so as to embrace said bar, and provided with a spring-bolt, and a spring-catch, F, attached to the lower sash, substantially as shown, and for the purpose set forth.

3. In combination with a window-frame, a depending bar, C, secured thereto, and spring-catches attached to the upper and lower sashes and adapted to engage with perforations and serrations in said spring-bar, the sliding bolts 40 of said spring-catches having attached thereto a flexible connection which passes through an eye, h, attached to the upper sash for operating the bolts, substantially as shown, and for the purpose set forth.

In testimony whereof I affix my signature in presence of two witnesses,

WILLIAM T. GILBERT.
